(57) **CLAIM**

The ornamental design for a bottle, as shown and described.

DESCRIPTION

FIG. 1 is a perspective view of a bottle according to the present invention;

FIG. 2 is a front elevation view thereof;

FIG. 3 is a right side elevation view thereof;

FIG. 4 is a top plan view thereof;

FIG. 5 is a bottom plan view thereof;

FIG. 6 is a section view of the bottle of FIGS. 1-5 taken along lines 6-6 in FIG. 2;

FIG. 7 is a perspective view of a bottle according to a second embodiment;

FIG. 8 is a front elevation view thereof;

FIG. 9 is a right side elevation view thereof;

FIG. 10 is a top plan view thereof;

FIG. 11 is a bottom plan view thereof;

FIG. 12 is a section view of the bottle of FIGS. 7-11 taken along lines 12-12 in FIG. 8;

FIG. 13 is a perspective view of a bottle according to a third embodiment;

FIG. 14 is a front elevation view thereof;

FIG. 15 is a top plan view thereof;

FIG. 16 is a bottom plan view thereof; and,

FIG. 17 is a section view of the bottle of FIGS. 13-16 taken along lines 17-17 in FIG. 15.

The broken lines shown represent unclaimed subject matter and form no part of the claimed design.

1 Claim, 6 Drawing Sheets
